PORTABLE INFLATABLE TRAFFIC DIVERTING DEVICE

Morris O. Weig, Lynbrook, N. Y.

Application July 21, 1954, Serial No. 444,744

1 Claim. (Cl. 116—63)

This invention relates to new and useful improvements in traffic diverting devices such as are set up on streets, roads and highways to route traffic around workmen, freshly painted road lines or signs or the like.

More particularly, the present invention proposes the construction of an improved traffic diverting device which can be compactly stored or stacked for transporting and which will not harm an automobile or other vehicle which by accident hits or runs over it.

As a further object, the present invention proposes forming a traffic diverting device with a heavy resilient base and an inflatable and collapsible resilient center portion.

Still further, the present invention proposes constructing the traffic diverting device so that it can be inflated into the familiar and convenient to handle conical shape.

Another object of the present invention proposes forming the traffic diverting device with a center portion which is conical when inflated and which can be coated with light reflecting paint or other traffic warning surface coatings.

A still further object of the present invention proposes constructing the traffic diverting device with a plurality of resilient tabs extending over the inflatable and collapsible resilient center portion to hold such portion flatly on the base in collapsed position and to bear against the sides of the conical center portion when inflated to assist in collapsing it when it is deflated.

For further comprehension of the invention, and of the objects and advantages thereof, reference will be had to the following description and accompanying drawings, and to the appended claim in which the various novel features of the invention are more particularly set forth.

On the accompanying drawings forming a material part of this disclosure:

Fig. 1 is a perspective view of a traffic diverting device constructed and arranged in accordance with the present invention.

Fig. 2 is a sectional view taken on line 2—2 of Fig. 1.

Fig. 3 is a view similar to Fig. 2 but showing the center portion of the device collapsed.

Fig. 4 is a top plan view of the structure as shown in Fig. 3.

Fig. 5 is a view similar to Fig. 2 but showing a modification of the invention.

Fig. 6 is another view similar to Fig. 2 but showing a still further modification of the invention.

Fig. 7 is a sectional view of the inflatable center member before it is formed to include a weighted circular tube.

The traffic diverting device of the present invention has a heavy base 15 of resilient material such as hard rubber, plastic or the like. The base 15 is circular or disc-shaped with a solid bottom surface 16.

A central circular recess 17 is formed in the top surface of the base 15 and a rim 18 is disposed on the top surface between the recess 17 and the peripheral or outer edge 19 of the base.

2

Extending from the rim 18 inwardly and overlying the recess 17 are a plurality of resilient tabs or members 20, 21 and 22 preferably formed integral with the base 15.

Inside the recess 17 on the base 15 is disposed an inflatable and collapsible resilient center portion or member 23 which is in a shape adapted to tower above the base as a cone when inflated. The center portion 23 has spaced side walls 24 and 25, side wall 24 being the outer wall and side wall 25 being the inner wall. In addition, center portion 23 has two spaced bottom walls 26 and 27, the lower wall 26 being fixed to the base 15 in the recess 17. Walls 24 and 26 and walls 25 and 27 are connected together and a top wall 28 connects the side walls 24 and 25. The top wall 28 is considerably thicker than walls 24 and 25 so as to provide a weight to facilitate the collapsing of the center portion 23.

An air valve 29 secured to side wall 24 at the base or closely adjacent thereto provides means to inflate and deflate the center portion 23 of the device.

When the center portion 23 is inflated as shown in Figs. 1 and 2, it rises over and towers above the heavy base 15 like a cone. The resilient tabs or members 20, 21 and 22 press inwardly against the outer side wall 24 of the center portion 23 so that when cap 30 is removed from air valve 29 these tabs 20, 21 and 22 will aid in deflating the center portion 23 and in collapsing it in the recess 17. Once the center portion 23 is so collapsed, the resilient tabs 20, 21 and 22 tend to hold it securely in the base recess 17 so that the device can be easily stacked, stored and transported.

In Fig. 5, the heavy base 15' is made integral with the resilient center member 23' which is covered with a comparatively thick cover wall 28' to facilitate the collapsing of the center portion 23' when the air valve 29' is open for deflating.

In other respects this form of the invention is similar to the previous form and corresponding parts may be recognized by similar reference numerals with a prime added.

It is to be understood that the base 15 or 15' may be made heavier by inserting or moulding into the base any desired weight material, such as sand, cement, lead, etc.

In Figs. 6 and 7, the conical-shaped, inflatable center member 35 is similar to that shown in the previous form of the invention illustrated in Fig. 5 and is provided with a comparatively thick core or top wall 36. The bottom annular edge 37 of the conical center member 35 is adapted to be folded upwardly as shown at 39 and then downwardly to form an annular tubing 40 which is filled with sand 41, or any other heavy material to act as a weight for holding the traffic diverting device on the ground.

The free bottom edge 37 of the conical center member is then heat sealed at 42 to close the annular tubing 40 and to prevent the sand, or the like, from escaping therefrom.

The bottom of the substantially conically shaped traffic diverting device is then covered with a circular air-pervious sheet material 43, preferably made of plastic material which will be heat sealed at 44 to the outer surface of the free edge 37 to form a conical, inflatable body 45. This body may be inflated through an air valve 46 which is normally closed by a suitable closure cap 47 and then the device may be readily used as a portable traffic diverting device and set up on streets, roads, etc.

This device may be collapsed by deflating the conical inflatable body 45 through its valve 46. A plurality of these devices may be stacked in collapsed condition for storing or transporting the same.

While I have illustrated and described the preferred embodiments of my invention, it is to be understood that I do not limit myself to the precise constructions herein

disclosed and the right is reserved to all changes and modifications coming within the scope of the invention as defined in the appended claim.

Having thus described my invention, what I claim as new, and desire to secure by United States Letters Patent is:

A portable traffic diverting device comprising a heavy base, an inflatable and collapsible center portion adapted to tower above said base when inflated and means at the base to inflate the center portion, said center portion being substantially conical when inflated, said heavy base consisting of sand or similar material enclosed in an annular tubing, said annular tubing being integral with the center portion of the device and having the free bottom edge of the said center portion first folded upwardly 15 and then downwardly to form a tube, the free bottom

edge of the said center portion being heat sealed, said sand or other weighting material being filled into the said annular tubing before heat sealing the bottom edge thereof, and a bottom disc made of plastic or the like material attached by heat sealing to the said bottom edge of the annular tubing portion to form an inflatable, substantially conical air-pervious portable traffic diverting device.
